FURNITURE

Henry Feldman, New York, N. Y.

Application March 30, 1937, Serial No. 133,787

18 Claims. (Cl. 312—164)

This invention relates to furniture. It is particularly directed to a combination desk and table and the like articles of furniture.

An object of this invention is to provide an article of furniture of the character described, which may be used as a desk and looks like a desk, and which may be easily converted into a table, and when converted will provide ample room for the knees and feet of persons sitting thereat.

Another object of this invention is to provide a rugged, compact and highly attractive article of furniture of the character described, which shall be relatively inexpensive to manufacture, easy to manipulate, comprise few and simple parts, and which shall yet be practical and efficient to a high degree in use.

Other objects of this invention will in part be obvious and in part hereinafter pointed out.

The invention accordingly consists in the features of construction, combinations of elements, and the arrangement of parts which will be exemplified in the construction hereinafter described, and of which the scope of application will be indicated in the following claims.

In the accompanying drawings, in which is shown one of the various possible illustrative embodiments of this invention,

Fig. 1 is a front elevational view of an article of furniture embodying the invention, and illustrating in dot-dash lines the position of various parts when converted into a table, and with parts in cross section;

Fig. 2 is a top plan view of the structure shown in Fig. 1 opened for use as a table; and with parts broken away and in cross-section;

Fig. 3 is a side elevational view of the structure shown in Fig. 2;

Fig. 4 is one end elevational view of the structure shown in Fig. 1;

Fig. 5 is an elevational view of the other end of the desk shown in Fig. 1;

Fig. 6 is an elevational, cross-sectional view of the upper portion of an article of furniture embodying the invention and illustrating a modified form thereof;

Fig. 7 is an end elevational view of the structure shown in Fig. 6, converted from a desk into a table;

Fig. 8 is an elevational cross-sectional view of the structure shown in Fig. 6, converted from a desk into a table;

Fig. 9 is a top plan view of the structure shown in Fig. 8;

Fig. 10 is a cross sectional view taken on line 55 10—10 of Fig. 8;

Fig. 11 is a front elevational view of a desk embodying the invention, illustrating a still further modified form of the invention, and with parts in cross section;

Fig. 12 is a cross-sectional view taken on line 5 12—12 of Fig. 11;

Fig. 13 is a top plan view of the desk when converted into a table;

Fig. 14 is a cross-sectional view taken on line 10 14—14 of Fig. 13; and

Fig. 15 is a transverse cross-sectional view illustrating a ball and socket means for limiting movement of the cabinets toward each other.

Referring now in detail to the drawings, particularly to Figs. 1 to 5, 10 designates an article of furniture embodying the invention, in the form of a combination desk and table. That is, the desk of Fig. 1 may be converted into a table as shown in Figs. 2 and 3. My improved article of furniture 10, comprises a desk top 11, to one end 11a of which there is fixed a vertical, narrow centrally located panel 12, extending down to the floor. The panel 12, is narrower in width than the desk top 11, and is centrally disposed between the front and rear edges of said table top. Fixed to the bottom end of the panel 12, is a supporting base 12a, and fixed to said base is a horizontal board 13, disposed centrally beneath the desk top 11 and somewhat narrower than panel 12.

Fixed to one end of the board 13, is a substantially square or oblong base 14. The base 14 is located beneath the other end 11b of the desk top 11, and is centrally disposed between the front and rear edges of said desk top, and is of less width than said desk top. The base 12a and the 30 base 14, may be supported on legs 12b and 14a, respectively, or casters, or any other suitable supporting devices.

Fixed to the underside of the desk top 11, is a vertical downwardly projecting, pivot pin 17. 40 The pin 17, is located centrally between the front and rear edges of the desk top 11, and directly over the center of the base 14. On the base 14, and directly beneath the pin 17, is a pin socket 19. Disposed between the base 14, and the desk top, is a cabinet 20 for drawers. The cabinet 20, has a bottom wall 21, a top wall 22, side walls 23 and 24, a front wall 25, and a rear wall 26. Fixed to the top wall 22, is a socket 27, receiving the pivot pin 17. Attached to the under side of the 50 bottom wall 21 of said cabinet 20, is a pin 28 journaled to the socket 19. The pins and sockets may be of any suitable type, and serve to mount the cabinet 20, between the base 14 and the desk top 11 for pivotal movement about a vertical axis. 55

The length of the cabinet from front to rear is preferably equal substantially to the width of the desk top 11. As shown in Fig. 2 in the drawings, width of the cabinet 20, from one side wall to the other, is preferably greater than the width of the base 14 from front to rear, so that when the cabinet is rotated from the position shown in Fig. 1, through an angle of 90°, to the position shown in Fig. 2, said base will be inset 5 from the side walls 23, 24 of the cabinet, whereby the toes of persons sitting at the table may project beneath the cabinet. The additional room for the feet adds to the comfort of persons sitting at the table on opposite sides of the cabinet 20.

Any desirable number of drawers 31 may be provided in the cabinet 20. The side wall 23 of the cabinet has vertical flanges 30 at the front and rear vertical edges thereof, forming a recess 33 for the purpose hereinafter appearing. Pivoted to the end edge 11b of the desk top 11, is a leaf 35, normally hanging by gravity in vertical position, as shown in Fig. 1, and being received within said recess 33, so that the front 20 and rear edges of said leaf cannot be seen from either the front or rear of the desk.

There is also pivoted to the other end edge 11a of the desk top 11, a leaf 36, normally hanging by gravity in vertical position. To support the leaf 36 in horizontal position, as shown in Figs. 2 and 3, there is pivoted to the front and rear vertical edges of the panel 12, a pair of similar, symmetrically disposed panels 40 and 41 hinged about the hinges 40a and 41a respectively. The panels 40 and 41 are normally in the same plane as the panel 12. On the outer vertical edges thereof the panels 40 and 41 have angular outwardly extending flanges 42 and 43, to cover the front and rear edges of leaf 36.

To convert the desk into a table, the leaf 35 is raised to horizontal position and the cabinet 20 swung through an angle of 90 degrees, to the position shown in Fig. 2. The cabinet 20 as shown in Fig. 2, when swung through an angle 45 of 90 degrees, about the vertical pins 17 and 28, will project beyond the end 11b of the desk top 11, to support the leaf 35. This manipulation furthermore provides room for the knees of persons sitting at the table on opposite sides of the cabinet. At the other end 11a of the table, the leaf 36 is lifted to horizontal position, and the panels 40, 41 swung inwardly through angles of 90 degrees, to the position shown in Fig. 2. In the position of Fig. 2, the panels 40 and 41 50 will support the leaf 36 and will give knee room for persons sitting on opposite sides of panel 12. The desk is then converted into a table, and will provide knee or leg room all around the table.

In Figs. 6 to 10 inclusive, there is illustrated 60 a combination desk and table, embodying a modified form of the invention. The combination desk and table 10a, illustrated in said figures, comprises a top structure 50, including a flat wall 51, to the front and rear edges of which 65 are fixed short, upstanding walls 52, supporting a desk top 53. The desk top 53 is spaced from the wall 51, forming a chamber 54 therewith, open at the opposite ends. The inner surfaces of the upstanding front and rear walls 52, are 70 formed with similar aligned grooves 57. The grooves 57 each comprises a horizontal central portion 58 adjacent the lower wall 51, upwardly and outwardly inclined portions 59 at opposite ends of said central portion, and short, horizontal end portions 60 extending outwardly from said 75

inclined portions, and disposed adjacent the desk top 53. The member 50 is supported at one end by a cabinet 20, pivoted about a central, vertical axis, and supported on a base (not shown), similar to the base 14. The other end 5 of member 50 may be supported by a vertical panel 62 having a width equal to that of the desk top. The panel 62 is pivoted by a central pin and socket connection 63, to the middle of one end of wall or board 51. The bottom of 10 said panel may also be pivotally supported by a base (not shown) through a pin and socket connection. The panel 62 may be turned through an angle of 90 degrees, as shown in Fig. 1 of the drawings, for the purpose hereinafter appearing.

Disposed within the chamber 54 are a pair of similar, symmetrically disposed extensible leaves 65. At the inner ends of said leaves and on opposite sides thereof are brackets 66, carrying 20 rollers 67, disposed within the grooves 57. At the outer ends thereof the leaves 65 have downwardly extending flanges 69, adapted to rest, one on the top of the cabinet 20, and the other on the vertical panel 62, as shown in Fig. 6. 25 Hinged to the under surfaces of said leaves 65, as on hinges 70 are transverse supports 71, adapted to be disposed between said leaves and the wall 51 when the leaves are within chamber 54.

To convert the desk into a table, the leaves 65 are pulled out and the cabinet 20 and panel 62 are turned through angles of 90 degrees each. As shown in Figure 8 of the drawings, one hinged support 71 rests on the turned cabinet 20, and 35 the other hinged support rests on the turned panel 62, to maintain the leaves in horizontal position. When the leaves are pulled out, the rollers 65 roll within the portions 58, 59 and 60 of the grooves 57.

Turning of the cabinet 20 and the panel 62 40 provides leg and knee movement necessary for persons to sit comfortably at the table.

The panel 62 may be of the full width of the desk, but when turned through an angle of 45 90 degrees is disposed along the longitudinal axis of the table, and is therefore out of the way of the feet or knees of a person sitting at the table. To collapse the table into a desk, the hinged supports 71 are swung upwardly 50 against the under sides of the leaves, the leaves are swung downwardly about the rollers 67, until said leaves are below the desk top 53. Said leaves may then be pushed inwardly within the compartment 54.

It will be understood that the leaves are collapsed one at a time. After the leaves are pushed 55 into the compartment 54, the cabinet 20, and panel 62, may be rotated back to normal position.

It will be understood that the desks 10 and 10a 60 may be provided with cabinets at both ends each pivoted about a vertical axis.

In Figs. 11 to 15 inclusive there is illustrated 65 a desk 80 convertible into a table and embodying another form of the invention. The article of furniture 80 comprises a horizontal rectangular member 81 supported at the ends 81a and 81b by a pair of spaced cabinets 82, provided with drawers 83 of any suitable construction.

Means is provided for slidably moving the cabinets 82 toward each other to the dot dash line positions of Fig. 11. To this end the under surface of the member 81 is formed with a pair of parallel slots 84, 85 adjacent the front and rear edges 86, 87 of said member 81, and extending 70

substantially the entire length of said member. Within each of the slots or grooves 84, 85 is a vertical rail casing member 88 having a bottom wall 88a formed with a central longitudinal slot 88b. Fixed to the top of each cabinet 82 are a pair of parallel front and rear elongated brackets 90, each having an upwardly extending vertical wall 91, projecting above the cabinet and through the slots 88b. The walls 91 each carry at the ends thereof a pair of rollers 92 disposed within the rail casing 88 on opposite sides of slot 88b. It will now be understood that the cabinets 82 are connected to the member 81 by a roller on rail connection. To limit the movement of the 10 cabinets inwardly toward each other at the dot dash line position of Fig. 11, each of the webs or walls 81 carries at the upper edge thereof, a spring pressed ball assembly 95; and the top walls 88c of the rail casings 88 are formed with 20 openings 96 into which the balls 95 will snap when the cabinets are centrally located, with the meeting surfaces at the midsection of the member 81.

On the member 81 are a pair of superposed table top members 100 and 101 of equal dimension and similar in size to the member 81. The members 100, 101 are hinged together by hinge 102 at the rear edges thereof.

Means is provided to permit the hinged together members 100, 101 to be slidably moved forwardly together, for a distance equal to half the width of the member 81, whereby the member 100 may then be swung open through an angle of 180 degrees to the position shown in Figs. 13 and 14 of the drawings. To this end the member 81 is formed in the upper surface thereof with a pair of spaced parallel grooves 105 parallel to the ends of member 81, and symmetrically disposed about the midsection of said member. 40 The grooves 105 terminate short of the front and rear edges 86, 87 of the member 81. Fixed to the underside of the member 101 and countersunk therein, are a pair of parallel guide members 107, slidably received within the grooves 105. 45 The members 107 are formed on the opposite side edges thereof, with grooves 108; and metal plates 109, fixed to the top of the member 81 and countersunk therein and disposed on opposite sides of the member 107 project into the grooves 50 108 to prevent lifting of the member 101 off the top of member 81. The front ends of the members 107 are spaced from the front ends of the slots 105 by a distance equal to half the width of the member 81, so as to permit the hinged together members 100, 101 to be slidably moved together forwardly for a distance equal to half the width of the member 81, at which the position of the front ends of the members 107 will contact the stops 110 at the front ends of said slots. 55 Thereafter the member 100 may be swung about the hinge 102 through an angle of 180 degrees to the position shown in Figs. 13 and 14.

It will now be understood that the article of furniture 80 as shown in Fig. 11 is a desk with cabinets at both ends. The piece of furniture 80 may be converted into a table by moving the cabinets 82 together, sliding members 100, 101 forwardly, and then opening up the member 100. In the position shown in Figs. 13 and 14, the 60 cabinets 82 are spaced from all edges of the table top 100, 101 providing ample knee or foot room for persons sitting at the table.

The table may be reconverted into a desk by swinging the member 100 over the top of the 65 member 101, then pushing the two together rear-

wardly to superimposed position with respect to member 81, and then pulling the cabinets 82 apart.

It will thus be seen that there is provided a 5 device in which the several objects of this invention are achieved, and which is well adapted to meet the conditions of practical use.

As various possible embodiments might be made of the above invention, and as various changes might be made in the embodiments set forth, it is to be understood that all matter herein set forth or shown in the accompanying drawings is to be interpreted as illustrative and not in a limiting sense.

Having thus described my invention, I claim as 15 new and desire to secure by Letters Patent:

1. An article of furniture comprising a top member, a cabinet, having drawers, supporting one end of said top member and being substantially of the same dimension, from front to rear, 20 as the width of the top member, means for pivotally connecting the cabinet to the top member about a vertical axis, the width of the cabinet from side to side being less than the width of the top member from front to rear, means to support the other end of said top member, a leaf connected to said top member, said cabinet being adapted to support said leaf in horizontal position upon rotating said cabinet about said vertical axis. 25

2. An article of furniture comprising a top member, a cabinet, having drawers, supporting one end of said top member and being substantially of the same dimension, from front to rear, 30 as the width of the top member, and means for pivotally connecting the cabinet to the top member about a vertical axis, the width of the cabinet from side to side being less than the width of the top member from front to rear, a leaf on 35 said top member adapted to be supported by said cabinet upon rotating the latter about said axis, and a member at the opposite end of and beneath said top member to support the other end of said top member, and extending to a front edge of said top member and rotatable about a vertical axis to a position spaced inwardly of said front edge and a second leaf on said top member adapted to be supported by said rotatable member in said spaced position thereof. 40

3. An article of furniture comprising a top 50 member, a cabinet, for drawers, supporting one end of said top member and being substantially of the same dimension, from front to rear, as the width of the top member and means pivotally connecting the cabinet to the top member 55 about a vertical axis, the width of the cabinet from side to side being less than the width of the top member from front to rear, means to support the other end of said top member and a leaf associated with said top member and movable with respect thereto to form an extension of said top member, said cabinet being adapted to project beyond one end of the top member when swung about said vertical axis through an angle of 90 degrees, and to support said leaf in the latter 60 position thereof. 65

4. As an article of furniture, a desk convertible into a table and comprising a desk top, a cabinet supporting the desk top adjacent one end thereof and being connected to said desk top for pivotal 70 movement about a vertical axis, a member adjacent the other end of the desk top pivotable about a vertical axis, and extensible leaves movably connected to said desk top, adapted to be supported by said cabinet and pivotable member re- 75

spectively upon rotating said cabinet and pivotable member about said axes.

5. As an article of furniture, a combination desk and table comprising a table top, a cabinet supporting one end of said table top, a leaf hinged to one end of said table top and hanging by gravity in vertical position, said cabinet being pivoted to the table top about a vertical axis and being adapted to project beyond said end of said 10 table top upon rotating said cabinet about said axis, whereby to support said hinged leaf when said leaf has been lifted to horizontal position and means to support the other end of said table top.

15. 6. As an article of furniture, a combination desk and table comprising a table top, a cabinet supporting one end of said table top, a leaf hinged to one end of said table top and hanging by gravity in vertical position, said cabinet being pivoted to the table top about a vertical axis and being adapted to project beyond said end of said 20 table top when said cabinet has been rotated about said axis, whereby to support said hinged leaf when said leaf has been lifted to horizontal 25 position, the other end of said table top being supported by a central panel and panels hinged about vertical axes to the front and rear portions of said panel, a leaf hinged to the table top adjacent said other end and being adapted to be supported by said pair of panels, when said last 30 mentioned leaf has been lifted to horizontal position and swinging said pair of panels outwardly about their vertical pivots.

7. As an article of manufacture, a desk convertible into a table, comprising a top member, a leaf slidably mounted with respect thereto and extensible therefrom, and a member supporting said top member and connected thereto for pivotal movement about a vertical axis, and being adapted when rotated to support said slidably 35 leaf when the latter is extended from said top member.

8. As an article of manufacture, a desk convertible into a table comprising a top member, a pair of cabinets supporting the opposite ends of said top member, means for slidably connecting said cabinets to said top member whereby said cabinets may be slidably moved toward the middle of said top member, and a pair of hinged together superposed members on said top member, one of said hinged together members being slidably mounted on said top member.

9. As an article of furniture, a desk convertible into a table, comprising a top member supported at one end by a cabinet movable with respect to said top member, said cabinet in one position thereof having a portion disposed adjacent an edge of said top member, said portion of said cabinet in another position of said cabinet being spaced from said edge of said top member to provide leg room for persons sitting at said article of furniture when converted into a table, means spaced from said cabinet to support the other end of said top member, and a pair of table top members connected with said first top member and movable relative thereto and to each other, said table top members being movable to positions projecting beyond other edges of said top member, said top member being supported wholly and 50 only by said cabinet and means.

10. As an article of furniture, a desk convertible into a table, comprising a top member supported at one end by a cabinet movable with respect to said top member, said cabinet in one position thereof having a portion disposed adjacent

an edge of said top member, said portion of said cabinet in another position of said cabinet being spaced from said edge of said top member to provide leg room for persons sitting at said article of furniture when converted into a table, means 5 spaced from said cabinet to support the other end of said top member, and a pair of table top members connected with said first top member and movable relative thereto and to each other, said cabinet in said other position thereof being 10 adapted to support one of said pair of table top members, and said means being adapted to support said other of said pair of table top members.

11. As an article of furniture, a desk convertible into a table, comprising a top member, a cabinet supporting one end of said top member and being disposed wholly beneath said top member and movably connected thereto, means spaced from said cabinet to support the other end of said top member, said cabinet in one position thereof having a portion disposed adjacent an edge of said top member, said cabinet in another position thereof being spaced inwardly of said edge of said top member to provide leg room for persons sitting at said edge of said top member, when said article of furniture is converted into a table, and a leaf connected to said top member and movable with respect thereto, said leaf being adapted to be moved to a position projecting beyond another edge of said top member, said top member being supported only by said cabinet and means.

12. As an article of furniture, a desk convertible into a table, comprising a top member, a cabinet supporting one end of said top member and being disposed wholly beneath said top member in one of its positions, and movably connected thereto, means spaced from said cabinet to support the other end of said top member, said cabinet in one position thereof having a portion disposed adjacent an edge of said top member, said cabinet in another position thereof being spaced inwardly of said edge of said top member to provide leg room for persons sitting at said edge of said top member, when said article of furniture is converted into a table, and a leaf connected to said top member and movable with respect thereto, said leaf being adapted to be moved to a position projecting beyond another edge of said top member, said cabinet being adapted to project 40 beyond said other edge of said top member in said other position thereof, and said leaf being supported in horizontal position by said cabinet when the latter is in said other position thereof.

13. As an article of furniture, a desk convertible into a table, comprising a top member, a cabinet supporting one end of said top member and being disposed wholly beneath said top member in one of its positions, and movably connected thereto, means spaced from said cabinet to support the other end of said top member, said cabinet in one position thereof having a portion disposed adjacent an edge of said top member, said cabinet in another position thereof being spaced inwardly of said edge of said top member to provide leg room for persons sitting at said edge of said top member, when said article of furniture is converted into a table, and a leaf connected to said top member and movable with respect thereto, said leaf being adapted to be moved to a position projecting beyond another edge of said top member, said cabinet being adapted to project 60 beyond said other edge of said top member in said other position thereof, and said leaf being supported in horizontal position by said cabinet 65 when the latter is in said other position thereof.

14. As an article of furniture, a desk convertible into a table, comprising a top member, a cabinet supporting one end of said top member and being disposed wholly beneath said top member in one of its positions, and movably connected thereto, means spaced from said cabinet to support the other end of said top member, said cabinet in one position thereof having a portion disposed adjacent an edge of said top member, said cabinet in another position thereof being spaced inwardly of said edge of said top member to provide leg room for persons sitting at said edge of said top member, when said article of furniture is converted into a table, and a leaf connected to said top member and movable with respect thereto, said leaf being adapted to be moved to a position projecting beyond another edge of said top member, said cabinet being adapted to project 70 beyond said other edge of said top member in said other position thereof, and said leaf being supported in horizontal position by said cabinet 75

when the latter is in said other position thereof, said cabinet being substantially of the same dimension from front to rear as the width of said top member, and the width of said cabinet from side to side being less than the width of said top member from front to rear.

14. As an article of furniture, a desk convertible into a table, comprising a top member, a cabinet supporting one end of said top member and being disposed wholly beneath said top member in one of its positions, and movably connected thereto, means spaced from said cabinet to support the other end of said top member, said cabinet in one position thereof having a portion disposed adjacent an edge of said top member, said cabinet in another position thereof being spaced inwardly of said edge of said top member to provide leg room for persons sitting at said edge of said top member, when said article of furniture is converted into a table, and a leaf connected to said top member and movable with respect thereto, said leaf being adapted to be moved to a position projecting beyond another edge of said top member, said cabinet being adapted to project beyond said other edge of said top member in said other position thereof, and said leaf being supported in horizontal position by said cabinet when the latter is in said other position thereof, a second leaf movably connected to said top member, and means connected with the means for supporting the other end of said top member, for supporting said second leaf in horizontal position.

15. A desk convertible into a table, comprising a top member, a pair of leaves hinged to the ends of said top member, and normally hanging therefrom by gravity in vertical position, a vertical member supporting one end of said top member, means on said vertical member for supporting one of said leaves in horizontal position upon lifting said leaf to said position, a base fixed to the lower end of said vertical member and disposed parallel to said top member, a cabinet interposed between said top member and base and being connected thereto for pivotal movement about a vertical axis, said cabinet being adapted to support the other leaf in horizontal position, when said leaf has been lifted to horizontal position and said cabinet has been rotated about its vertical axis.

16. A desk convertible into a table, comprising a horizontal table top, a base below said table top, a cabinet interposed between said table top and base and disposed adjacent one end of said

table top, means for connecting said cabinet to said table top and base for rotation about a vertical axis, a leaf movably connected to said table top and adapted to be supported by said cabinet in one angular position of said cabinet, and means interconnecting said base and table top to support the other end of said table top.

17. An article of furniture comprising a horizontal top member, a pair of vertical members wholly and jointly supporting said top member and being movably connected thereto, each of said vertical members in one of its positions being disposed wholly beneath said top member and having a portion disposed adjacent an edge portion of said top member and in another of its positions, spaced from said edge portion of said top member, a pair of leaves movably mounted on said top member, and being movable relative to one another and adapted to be moved to positions projecting beyond other edge portions of said table top.

18. As an article of furniture, a desk convertible into a table, comprising a top member, a cabinet supporting one end of said top member and being disposed wholly beneath said top member and movably connected thereto, means spaced from said cabinet to support the other end of said top member, said cabinet in one position thereof having a portion disposed adjacent one edge portion of said top member, said cabinet in another position thereof being spaced inwardly of said edge portion of said top member to provide leg room for persons sitting at said edge portion of said top member, when said article of furniture is converted into a table, a leaf movably connected to said top member and adapted to be moved to a position projecting beyond a second edge portion of said top member, said top member being supported only by said cabinet and means, said means being movably connected to said top member and, in one of its positions, being disposed wholly beneath said top member and having a portion disposed adjacent the first edge portion of said top member, said means in another of its positions being spaced inwardly of said last mentioned edge portion of said top member, and a second leaf connected to said top member, and movable with respect thereto and with respect to said first leaf, said second leaf being adapted to be moved to a position projecting beyond a third edge portion of said top member.

HENRY FELDMAN.
